UNITED STATES PATENT OFFICE.

GEORGE E. SOVEREIGN, OF POTTERSVILLE, NEW JERSEY.

GAME APPARATUS.

SPECIFICATION forming part of Letters Patent No. 498,451, dated May 30, 1893.

Application filed July 1, 1892. Serial No. 438,661. (No model.)

To all whom it may concern:

Be it known that I, GEORGE E. SOVEREIGN, a citizen of the United States, residing at Pottersville, in the county of Hunterdon and State of New Jersey, have invented certain new and useful Improvements in Game Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to provide an amusing, instructive and entertaining game and at a comparatively small cost.

The invention consists in the improved game apparatus and in the arrangement, combination and manipulation of the several parts thereof, as herein set forth and finally pointed out in the claim.

Referring to the accompanying drawings, in which similar letters of reference indicate 25 corresponding parts in each of the figures where they occur, Figure 1, represents a plan view of the game board; and Figs. 2 and 3 represent ornamental blocks or figures designed to be employed in playing the game.

30 In said drawings A, A, and B, B, indicate battle fields each of which is divided into a series of squares or spaces denoted by stars, upon which the opposing forces or men (the blue and the gray), are placed, as in line of battle. The center b' of the broad space C between the opposing forces, is designed to be occupied by the generals or commanders as their headquarters their several stations or tents being denoted also by stars at each corner or angle of the center square or space C'. The remainder of the broad space is traversed obliquely by roads, D, from each battle field, which converge at the safety line E, at the center. Roads F, G, and H are also laid out 45 between at the rear and at each side or flank, of the two regiments respectively on each side. At the flanks of the two armies are prisons or hospitals, indicated by I.

The game is played as follows, to wit:—The 50 battle field on one side is occupied by the boys in blue, and on the other by the boys

in gray, the generals respectively occupying their headquarters at the center, and the men or privates the two rear rows of stars on each side. The players, of whom there may be two or four, move the men on the opposing sides, one at a time, alternately, toward each other, from star to star diagonally, until the front line or row of stars is reached whereon they can be moved side wise in either direction, if 55 there are no men in the way, and from whence the enemy's ranks or lines are reached by moving through the oblique roads to and from the safety line E. When a man is on the said safety line he cannot be captured but, beyond 60 it, on either side is within the enemy's lines and when there he is in danger of being captured if on a road leading directly to a star or if on or beyond the front line of stars. If 65 a man is moved on the enemy's side so as to avoid being captured and reach the enemy's extreme rear the player takes two of the enemy's prisoners but the man in the rear is of no further use and so remains until the game is finished. The generals I can be brought 70 into engagement at any stage of the game by moving them, one at a time, to the safety line, thence through the road leading to the first star, thence in either direction to any star not occupied by your own man and assist in the 75 capture of any of the enemy who may be found on a star in your path. The generals can be moved in any direction, passing to the enemy's side in same manner as privates. When four play each is entitled to move one 80 general and the men in one division or regiment. In moving the player captures a man or men of the enemy who is found in the way of the man or general he is moving, and places him or them in the prison or in the rear until 85 the game is ended. When all the men and one general on one side are taken prisoners a game is finished, the remaining general surrendering. The men upon one side are designed to be blue and those on the other gray 90 and may be of any desired shape the generals being further distinguished by size, badges or marks to indicate their rank. The stars, which may be understood to indicate States, and the roads, &c., may also be in contrasting colors so as to be easily distinguished. 95 The manner of playing the game may be 100

varied from that herein given, if desired, as may be agreed upon by the players before the play is commenced.

Having thus described my invention, what 5 I claim as new, and wish to secure by Letters Patent of the United States, is—

The herein described game consisting of a board or chart having two battle fields upon each side thereof divided into spaces, a portion 10 of which spaces is distinguished by stars or other arbitrary characters, blank spaces between and at the rear and sides of the said fields to represent roads, a broad space across the middle of the board between the fields, 15 the broad space being provided with a square at the center and with characters to represent

the headquarters of the officers, and a central line upon each side of the square to represent the safety line, said broad space being further provided with diagonal lines crossing the 20 space to represent roads and converging at the safety line, characters at the flanks of the two battle fields upon each side to represent prisons or hospitals, substantially as set forth.

In testimony that I claim the foregoing I 25 have hereunto set my hand this 17th day of June, 1892.

GEORGE E. SOVEREIGN.
